UNITED STATES PATENT OFFICE.

JAMES F. FELLOWS, OF TROY, NEW YORK.

MACHINE FOR FOLDING AND PRESSING THE EDGES OF FABRICS.

SPECIFICATION forming part of Letters Patent No. 435,137, dated August 26, 1890.

Application filed February 24, 1890. Serial No. 341,383. (No model.)

To all whom it may concern:

Be it known that I, JAMES F. FELLOWS, a citizen of the United States, residing at Troy, county of Rensselaer, and State of New York, have invented certain new and useful Improvements in Machines for Folding and Pressing the Edges of Fabrics, of which the following is a specification.

My invention relates to such improvements; and it consists of the novel construction and combination of parts, hereinafter described and subsequently claimed.

Reference may be had to the accompanying drawings, and the letters of reference marked thereon, which form a part of this specification.

Similar letters refer to similar parts in the several figures herein.

The object of my invention is to provide a machine that will fold curved as well as straight edges of fabric and in a continuous operation so break and press the fold that it will remain substantially intact during successive stages of manufacture into wearing apparel until permanently secured by stitching.

Figure 1 of the drawings is a top plan view of my improved machine. Figs. 2 and 3 are respectively side and front end elevations of the same. Fig. 4 is a view of the folder detached. Fig. 5 is a cross-section of the same, taken on the broken line 5 5 in Fig. 4. Fig. 6 is a view of a sheet-metal blank before the same is bent to make a folder. Fig. 7 is a top plan view of one of the cogged or fluted wheels detached. Fig. 8 is a central vertical section of the same. Fig. 9 is a plan view showing the relative position of the lower wheel, folder, and fabric while in use, the upper wheel being removed and a portion of the folder-shank broken away. The last six figures are shown upon an enlarged scale.

A is the frame of the machine, which may be secured to a bench or bed-plate A² by set-screws A'. The frame is provided with suitable bearings for the horizontal shaft A³, upon one end of which is fixed the driving-pulley A⁴, provided with a groove A⁵ to receive a power-belt, and with a crank-handle A⁶ to be actuated by hand-power when other

power is not desired. The other end of the shaft is provided with the detachable wheel B, adapted to be engaged by and actuate the similar wheel B'. Each of these wheels is provided on its periphery with a double series of cogs or flanges a and b, the flanges in one series being located opposite the flutes in the other series on the same wheel, so that when the wheels are brought into engagement with each other a flange upon each wheel enters a flute upon the other wheel at the same time. The wheel B has a stem (shown by dotted lines in Fig. 2) which enters the hollow shaft A³ and is held therein by a set-screw A⁷. The wheel B' is provided with a spindle B², rotary in suitable bearings in the oscillatory end of the arm B³, the other end being pivoted to the main frame at A⁸. The end of the spindle B² is provided with a groove B⁴, adapted to receive the holding-pin B⁵, inserted in an aperture in the oscillatory arm. By removing this pin, cogged or fluted wheels of various sizes and modified forms can be successively substituted for the wheel B'. The wheel B can likewise be changed by loosening the set-screw. The lower wheel B projects up through an opening B⁶ in the plate B⁷, which plate is supported by the main frame. The folder C serves to fold the edge of the fabric and guide the folded edge in between the wheels. This folder is adjustably secured to the plate B⁷ by means of the thumb-screw C' in the folder-shank into a threaded aperture in the plate. The inner edge of the folder is so formed as to present a curved or beveled edge C⁸, terminating in the point C⁹. I also provide means for varying the pressure of the wheels upon the folded edges of fabric as it is fed from the folder in between them, consisting of the lever D, fulcrumed at D¹⁰ upon the frame and adapted to engage with the oscillatory wheel-supporting arm B³. The end of the lever D is connected by link D² (shown in Fig. 3 only) with the treadle D³. By pressing down upon the treadle the wheels are pressed together, and by releasing the treadle the wheels are separated, as shown in Fig. 2, by the coil-spring D⁴, which acts upon oscillating arm B³ to lift its wheel-supporting end, the arm resting

upon the upper end of the spring and moving in a sideway or slot in the upper end of the post A², erected from the main frame.

The dotted lines in Fig. 3 show the movement of the lever D and actuating-treadle.

It is obvious that the fabric-edge can be folded and drawn between the wheels by hand, the wheels being revolved by the moving fabric or folded by various well-known 10 folders.

I prefer the use of a folder capable of lateral as well as longitudinal adjustment in connection with my improved form of wheels. In folding sharply-curved edges of fabric the 15 folded-over edge of fabric is necessarily considerably fulled, which prevents the folded-over edge from lying down flat upon the main part of the fabric unless the transverse folds induced by the fullness, as well as the main 20 longitudinal fold, are thoroughly pressed down and broken. By means of the double series of cogs I secure double the number of transverse breaks in the folded edge in the same longitudinal space, and also produce a 25 longitudinal ridge or break F in the folded-over portion, as shown in Fig. 9, which divides the transverse breaks F' produced by the cogs. This longitudinal ridge also serves to permit a slight disturbance or lifting of 30 the edge of the folded-over portion of the fabric without opening the main fold. The diagonal slot C² in the folder-shank permits of a lateral as well as longitudinal adjustment of the folder, and the folder can be so adjusted laterally as to cause the folded-over 35 portion of the fabric to be equally engaged

by both series of cogs on each of the wheels, as shown in Fig. 9, when curved work is to be executed, or so as to cause the whole of such folded-over portion to be engaged by 40 one series only in straight work, thus reducing the amount of power required to properly press the folded edge.

What I claim as new, and desire to secure by Letters Patent, is—

1. In a machine for folding and pressing the edge of fabrics, the combination, with a wheel fixed upon a rotary shaft and provided with a double series of peripheral cogs or flanges, having the flanges in one series located opposite the flutes in the other series, of a similar wheel rotary in suitable bearings, an oscillatory arm supporting such bearings, means for oscillating such arm, and means for rotating the wheel-supporting 50 shaft, substantially as described.

2. In a machine for folding and pressing the edge of fabrics, the combination, with a pair of coacting wheels, each of which is provided with a double series of peripheral cogs 60 or flanges, having the flanges in one series located opposite the flutes in the other series, of a folder-guide laterally adjustable relatively to such wheels, substantially as described.

In testimony whereof I have hereunto set my hand this 19th day of February, 1890.

JAMES F. FELLOWS.
